UNITED STATES PATENT OFFICE.

GEORGE F. GREEN, OF BAZETTE, TEXAS.

COMBINED BUCKLE AND HOOK.

SPECIFICATION forming part of Letters Patent No. 787,570, dated April 18, 1905.

Application filed November 22, 1904. Serial No. 233,847.

To all whom it may concern:

Be it known that I, GEORGE F. GREEN, a citizen of the United States, residing at Bazette, in the county of Navarro and State of Texas, have 5 invented certain new and useful Improvements in a Combined Buckle and Hook; and I do declare the following to be a full, clear, and exact description of the invention, such as will enable others skilled in the art to which it appertains to make and use the same.

My invention relates to improvements in combined back-band buckle and trace-hooks; and it consists in certain novel features of construction, combination, and arrangement of 15 parts hereinafter described and claimed.

The object of my invention is to provide a simple, comparatively inexpensive, durable, and efficient device of this character by means of which a trace may be properly supported 20 and held without chafing or bruising the side of the draft-animal.

The above and other objects, which will appear as the nature of my invention is better understood, are accomplished by the construction 25 illustrated in the accompanying drawings, in which—

Figure 1 is a front elevation of my improved combined back-band buckle and trace-hook, showing the application of the same. Fig. 2 is a vertical sectional view taken upon the 30 line 2 2 of Fig. 1, and Fig. 3 is a perspective view of the buckle and hook with the back-band and trace removed.

Referring to the drawings by numeral, 1 35 denotes a trace of any form, 2 a back-band, and 3 my combined buckle and hook, which comprises a base-plate 4 of rectangular form, provided along its side edges with right-angular flanges 5. Adjacent to the upper end of the 40 central portion of the base-plate 4 are formed two transversely-extending parallel slots 6 and 7, the latter of which has formed along its upper wall or edge a series of downwardly and outwardly projecting teeth or spurs 8. 45 In the side flanges 5 of the buckle adjacent to their centers are formed two alining recesses 9, which are preferably shaped as shown and extended approximately one-half the depth of said flanges. Pivotedly mounted in alining 50 openings 10, formed in the side flanges 5 ad-

jacent to their upper ends, is a swinging hook 11, which is preferably formed of wire bent as shown. The said hook has its lower end turned inwardly, as shown at 12, passed upwardly, as at 13, and then outwardly, as at 14, 55 in order to prevent the trace from becoming disengaged from it.

In use the back-band 2 is passed downwardly through the upper slot 6, over teeth 8, then through slot 7, then down the rear or inner face of said base-plate 4, then up over the front face of the same between the side flanges 5, and then through the slot 6, as clearly shown in Fig. 2 of the drawings. It will be seen that when the back-band is thus engaged 60 with the buckle the teeth 8 will securely hold the former upon the latter, and since the under side or face of the base-plate 4 is covered by a portion of said back-band the side of the draft-animal will be protected from the metal 65 portion of the device. The trace 1 is engaged with the portion 12 of the hook 11, as shown, and is seated in the recesses 9, formed in the centers of the sides 5 of the buckle-plate. Owing to the central disposition of said 70 recesses 9 with respect to the plate, the pressure or strain exerted by the trace upon the buckle will be distributed equally over the entire surface of the plate 4, and owing to the fact that the recesses 9 are not as deep as the 75 depth or width of the flanges 5 the trace 1 will be held away from the side of the animal to prevent it from rubbing or otherwise injuring the animal. It will be further noted that the device is of exceedingly simple and 80 durable construction and that it may be manufactured at a comparatively small cost.

From the foregoing description, taken in connection with the accompanying drawings, the construction and operation of the invention 85 will be readily understood without requiring a more extended explanation.

Various changes in the form, proportion, and the minor details of construction may be resorted to without departing from the principle or sacrificing any of the advantages of 90 this invention.

Having thus described my invention, what I claim as new, and desire to secure by Letters Patent, is—

1. A device of the character described comprising a base-plate having side flanges formed with alining recesses and a pivotally-mounted hook having an inturned end adapted to engage a trace to hold the same in said recesses, substantially as described.
2. A device of the character described comprising a base-plate having side flanges formed in their outer edges with centrally-disposed alining recesses, and a hook pivotally mounted in said side flanges and having an inturned end adapted to engage a trace to hold the same in said recesses and above said base-plate, substantially as described.
- 15 3. A device of the character described com-

prising a base-plate having side flanges formed with alining recesses, a hook pivotally mounted between said flanges and having an inturned end to engage a trace to hold the same in said recesses, and means upon the said base-plate 20 for attaching a back-band thereto, substantially as described.

In testimony whereof I have hereunto set my hand in presence of two subscribing witnesses.

GEORGE F. GREEN.
